UNITED STATES PATENT OFFICE.

ROBERT T. PARKER, OF FAIRFIELD, NEBRASKA.

POOL-TABLE BALL-CARRIER.

SPECIFICATION forming part of Letters Patent No. 357,853, dated February 15, 1857.

Application filed July 19, 1856. Serial No. 208,448. (No model.)

To all whom it may concern:

Be it known that I, ROBERT T. PARKER, of 5
Fairfield, in the county of Clay and State of
Nebraska, have invented certain new and use-
ful Improvements in Pool-Table Ball-Carriers;
and I do hereby declare that the following is
a full, clear, and exact description thereof,
reference being had to the accompanying draw-
ings, and to the letters of reference marked
thereon, which form part of this specification,
in which—

Figure 1 is a perspective view of my im-
proved ball-carrier as applied to a pool-table.
Figs. 2, 3, and 4 are details of parts of the car-
rier.

This invention relates to improvements in
ball-carriers for pool-tables; and it consists in
the construction and novel arrangement of
parts, hereinafter described, and pointed out in
the claims.

Before proceeding to describe my invention
in detail I will state that I am aware that ball-
carriers have been made which conduct the
balls from the several pockets of a pool-table
to a proper receptacle located at a suitable
position for easy access by the players.

My invention therefore relates more par-
ticularly to the construction of the carrier-
frame, which I shall now proceed to describe.

Referring by letter to the accompanying
drawings, A designates a pool-table having
the usual number of pockets A' and outstand-
ing cushion-supporting frame A².

B designates the carrier-frame extending
35 along the opposite sides of the table, slightly
inclined toward and connecting with a basket
or receptacle, H, into which any balls that are
in the frame will roll by gravity. The con-
struction of the frame B on both sides of the
40 table being similar, the description of one side
will suffice.

The bottoms of the pockets A' of the table
are open, and have secured to them rings J, of
45 metal or other suitable material, which are of
sufficient diameter to admit the balls which
roll into the pockets to drop through them.

To the ring J of the pocket A', at the end of
the table opposite basket H, is secured, by a
50 suitable number of short cords or wires, a U-
shaped hanger, b, with its mouth upward, so
that it offers no obstruction to the passage of

the ball through the ring. At suitable dis-
tances apart upon hanger b are secured the
ends of bars or rods D, which are preferably
made of stiff wire and soldered to the hanger. 55
The rods D form the carrier-way, and are pref-
erably three in number, one being at the lowest
or central part of the hanger and the others at
equal distances on opposite sides thereof, as
shown in Fig. 3. The ends of the rods D pro-
ject slightly beyond the hanger b, as shown,
and are curved upward and inward in such
manner as to prevent the escape of the ball
from the carrier upon the floor. The rods D
run parallel, and slightly incline downward 65
from the first hanger b to the pocket at the op-
posite end of the table, where they turn on an
easy curve and connect with the basket H. The
rods are secured to the several pockets of the
table by hangers b and connections similar to 70
that before described.

B' designates bands or rings placed upon the
rods D at suitable intervals, and to which the
rods are secured. The bands B' both strengthen
the wires and keep them in proper relative 75
position as regards each other.

F designates metal bands similar in size to
bands B'; but provided with eyes or loops, f f'.
These bands F are secured on the rods about
centrally between the pockets of the table and 80
the bands B on the sides of the table, and are
connected by short links G, which engage the
loops f, with suitable screw-eyes or staples, G',
secured to the under surface of the cushion-
frame A². A band, F, and its attachments are 85
secured to the ends of the rods, where they
connect with the basket H, and support the
latter vertically. By means of the bands F the
inclination of the carrier may be adjusted so
as to give the right amount of "pitch" to the
carrier to conduct the balls to the basket.

H designates the basket, which may be of
any suitable construction, but is preferably
woven, as shown in drawings, so that the balls
will not be injured when they pass therein. 9.
The basket should be of sufficient size to hold
all the balls required in playing a game upon
the table.

The carrier, being made as described, is very
light, cheap, and durable, and can be easily at-
tached to any pool-table without injuring the
same, and no dust will collect on the carrier
100

sufficient to injure or impede the progress of balls therein. It will also be observed that the carrier, being applied to the table beneath the cushion-frame, offers no obstruction to the 5 players, and that the balls will make but very little if any noise in moving through the carrier.

Having described my invention, I claim—

1. A ball-carrier for pool-tables, consisting 10 of a frame, B, composed of parallel rods D, and hangers b, secured to rings J, in the bottom of the table-pockets, and intermediate supporting looped rings, F, and a basket, H, all constructed and arranged to operate substantially as and for the purpose specified.

2. The combination, with a pool-table having open-bottom pockets, of a frame, B, composed of parallel rods D, hangers b, secured to the pockets, and intermediate supporting- 20 rings, F, and their connections, whereby the pitch of the carrier can be regulated, and the receiving-basket H, all constructed substantially as and for the purpose specified.

3. In a ball-carrier for pool-tables, the combination, with the pockets A', having rings J 25 secured to their lower open ends, of the carrier-frame B, composed of hangers b, suitably connected to the rings J, parallel rods D, united to the hangers, intermediate stiffening rings, B', and supporting-rings F, having eyes f, 30 their connecting-links G, and screw-eyes G', and the receiving-basket H, the frame being suitably inclined to cause the balls when dropped into it to roll into the basket, all constructed and adapted to operate substantially 35 in the manner and for the purpose specified.

In testimony that I claim the foregoing as my own I affix my signature in presence of two witnesses.

ROBERT T. PARKER.
